SHOWER HEAD AND METHOD OF MAKING
THE SAMEChester W. Hathaway and Ernest Krumsiek,
Decatur, Ill., assignors to Mueller Co., Decatur,
Ill., a corporation of Illinois

Application April 18, 1935, Serial No. 17,142

3 Claims. (Cl. 299—141)

The present application relates to a shower head and a method of making the same.

One of the objects of the invention is to provide a shower head from which water will be delivered in the most efficient and desirable form of stream and which may be readily cleaned.

Another object of the invention is to provide an economical and very efficient method of producing shower heads.

Other objects and advantages of the invention will be apparent from the following description and drawing, in which,

Figure 1 is a perspective view of the shower head,

Figure 2 is a longitudinal sectional view through the head,

Figure 3 is an end view,

Figure 4 is a view partly in longitudinal section showing the flow obstructing disc in lowered or cleaning position, and

Figure 5 is an enlarged fragmentary view diagrammatically showing the method of forming the flow obstructing disc.

The shower head of the present invention includes a shell or body 10 which is substantially bell-shaped and has its upper end threaded to receive a collar 11 by means of which the spherical end of a connection 12 may be secured to the body. In use, the connection 12 is threaded upon the end of a water pipe as shown in Figure 1, thereby supporting the head. The inlet end of the shell is provided with the usual resilient washer 13 against which the spherical end of the connection 12 bears to be tightly sealed to the shell. The arrangement described above obviously permits the shower head to be moved angularly with respect to the connection 12 in order that the stream of water may be directed as desired.

The outlet end of shell 10 is provided with an opening 14, the inner or bounding surface of this opening being downwardly and outwardly inclined, that is, diverging. This conformation may be given during the casting or machining of the shell. A flow obstructing disc 15 is secured in the opening 14 by means of a stem 16, the body portion of stem 16 being threaded to engage a threaded opening 17 in a spider 18 formed integrally with the shell 10. The lower portion or head of stem 16 is provided adjacent its lower end with a flange 19, and in the manufacture of the stem, the peripheral surface of the flange 19 is inclined so as to be outwardly divergent as shown in Figures 2 and 3 and is also provided with circumferentially spaced notches 20, each notch preferably being semi-cylindrical in form. The

flange 19 of stem 16 engages in an aperture 21 formed centrally of the flow obstructing disc 15 and, in the completed device, the wall of the aperture 21 also diverges to be substantially parallel with the peripheral surface of the flange 19. Since the peripheral surface of the flange 19 is divergent or inclined, the flow obstructing disc 15 will be supported thereon. Also, in the completed form of the flow obstructing disc 15, its peripheral surface 22 is inclined or tapered, the point of greatest diameter being its outer or lower edge 23. Circumferentially spaced notches 24, preferably semi-cylindrical in shape, are formed in the peripheral surface 22 of disc 15. The inclination of the peripheral surface 22 of disc 15 is such that when the disc is fitted in the shell 10, this surface will be substantially parallel with the bounding surface of the outlet 14 of the shell.

In assembling the elements of the shower head, the stem 16 is passed through the disc 15 and a pin or other retaining member 25 is then placed in a diametrically extending aperture in the stem. The stem may then be threaded through the aperture 17 of the spider 18, being turned by means of the flat-surfaced extension 16a at its lower end. A nut 26 is placed upon the upper end of the stem 16 as shown in Figures 2 and 3. The stem 16 is rotated to bring the lower edge of stem flange 19 approximately opposite the lower edge of the aperture 21 in disc 15 and to bring the lower edge 23 of the peripheral surface 22 of disc 15 approximately opposite the lower edge of the bounding surface of outlet opening 14.

In use, water will issue from the apertures defined by the notches 20 and 24 and the relation described above of these notches to the surfaces which they oppose will cause the water to issue in two concentric and circular streams of diverging jets. The outer stream will be formed by the notches 24 in the periphery of disc 15 and the inner stream will issue from the notches 20 in stem 16.

In order to clean the head, the stem 16 is rotated by grasping or engaging the flattened surfaces 16a and the stem thereby moved downwardly in the shell. The downward movement of the stem 16 will bring the pin 25 into contact with the disc 15, forcing the latter downwardly should it tend to stick in the shell and so that its periphery will be clear of the shell, as shown in Figure 4. Contact of the nut 26 with the spider 18 will limit the downward movement of the stem, preventing the disc and stem from falling from the shell. Because of the fact

that the pin 25 is spaced above the flange 19 a distance slightly greater than the thickness of the disc 15, the disc may be moved upwardly and against the pin from the position shown in Figure 4, to permit the peripheral surface of the stem flange 19 and the notches 20 therein to be readily cleaned. The cleaning may be accomplished by use of a brush or the like, or by permitting water to flow through the head with the elements in the position described above.

In forming the shower head of the present invention, the bounding surface of the outlet opening 14 of shell 10 is made outwardly divergent and the inclined surface about the stem 16 is formed on such an angle that it will be slightly less inclined than the bounding surface of opening 14 when in assembled position in the shell.

The disc 15 is flat in the first stages of its formation and its peripheral surface 22 and the bounding surface of aperture 21 are at right angles to the faces of the disc, all as indicated by solid lines in Figure 5. The semi-cylindrical notches 24 in the periphery 22 of the disc are formed in the disc with their axes substantially parallel to the axis of the disc as indicated by the line A in Figure 5. With the notches 24 formed in the disc, it is bent to the concavo-convex shape indicated by the dotted lines in Figure 5, thereby causing the bounding surface of the central aperture 21 to diverge outwardly and downwardly and the periphery 22 to have the same lines. This conformation of these surfaces will naturally cause them to be in the desired relation to the bounding surface of the shell outlet and the stem 16 when the head is assembled.

By bending the disc 15 to the shape shown in dotted lines after the notches have been formed therein and also after the aperture 21 has been formed in the usual manner, the final shape of the disc is obtained by a much more economical process of manufacture than would be the case were the disc concavo-convex throughout its manufacture and if the central aperture 21 and the periphery 22, including the notches 24, formed to their final shape by machining alone or by casting. Obviously, were the disc 15 flat in final form and provided with diverging notches, it would be necessary to machine inclined surfaces on the edge of the disc and about the aperture 21 and also to form the notches 24 on an angle. It will therefore be appreciated that the method

of the present invention is much simpler and cheaper than the manufacturing processes usually followed.

We claim:

1. A shower head comprising a shell including an outlet opening having an outwardly divergent bounding wall, a centrally apertured concavo-convex disc positioned in the opening with its convex surface outermost, the wall of the disc aperture being diverged toward the convex surface, a stem secured in the shell and extending through the disc aperture, the stem having an inclined and notched peripheral surface thereon substantially opposite to and of less inclination than the wall of the shell opening, the peripheral surface of the disc being notched and substantially parallel to the bounding surface of the shell outlet opening. 5

2. The method of making a shower head including a shell and a flow-obstructing disc, comprising forming in the shell an outlet opening having an outwardly divergent bounding surface, forming notches in the peripheral surface of a flat disc with the axes of the notches substantially at right angles to the major surface of the disc, and bending the disc to concavo-convex form to position its peripheral surface at an angle to its axis and substantially parallel to the bounding surface of said opening. 10

3. The method of making a shower head including a shell provided with an outlet opening, a centrally apertured flow-obstructing disc positioned in the opening and a stem adapted to contact with the edge of the disc aperture and secured in the shell, comprising forming the shell outlet opening with an outwardly divergent bounding surface, forming about the stem an inclined and notched surface having less inclination than the outlet opening bounding surface, and forming the flow-obstructing disc from a flat apertured disc having its peripheral surface and the bounding surface of the aperture therein at right angles to its major surface, forming notches in the peripheral surface of the disc, the axes of the notches being substantially parallel to the disc axis, and bending the disc to concavo-convex form to respectively position its peripheral and apertured bounding surfaces substantially parallel to the bounding surface of the outlet opening and said surface about the stem. 15 20 25 30 35 40 45 50
